UNITED STATES PATENT OFFICE.

BARTON A. PROCTOR, OF NEW YORK, N. Y., ASSIGNOR TO NEWS PROJECTION CORPORATION, OF NEW YORK, N. Y., A CORPORATION OF NEW YORK.

TENSION CONTROL FOR TICKER TAPE.

Application filed February 26, 1926. Serial No. 90,982.

This invention relates to news projection machines in general, and more particularly to machines for projecting the images from a ticker tape or the like, and to mechanism 5 for controlling the tension on the portion of the tape exposed to the light rays for projection.

With news projecting machines associated with a printing mechanism such as a stock 10 quotation projecting machine in which the printing mechanism prints on the tape during the period of projection, considerable jar is transmitted to the tape receiving the impressions. If this jar, which is generally 15 referred to as the jump, is transmitted to the portion of the tape being projected, obviously the projected images will chatter or jump while moving along the projection screen. I have heretofore provided a mechanism 20 for overcoming this jump or jar, illustrated and claimed in my Patent No. 1,299,024, issued April 1, 1919.

Among the objects of the present invention, it is aimed, to provide an improved 25 mechanism for dissipating or absorbing the jar or jump in the tape before it reaches the projecting position, which mechanism comprises a resistance element or friction creating element and a tape drawing out 30 element, the friction creating element operating with the portion of the tape located between the tape printing mechanism and the projecting position whereby, as the printing mechanism feeds the tape to the 35 friction creating element, the latter element will temporarily resist the pull of the drawing out mechanism to form a loop in which the jar or jump will be dissipated to prevent transmitting the jar or jump to the 40 portion of the tape disposed in the projecting position.

Specifically, the present invention still further aims to provide an improved mechanism for dissipating or absorbing the jar or jump in the tape before it reaches the projecting position of a news projecting machine in which a support is provided and a loop forming device extends into the path of movement of the tape and cooperates with 45 the support to impede the free passage of the tape to the projecting position thereby to cause a loop to be formed in the tape between the printing mechanism and the projecting position in which loop the jar or jump will be dissipated to prevent transmit-

ting the jar or jump to the portion of the tape disposed in the projecting position.

Specifically, the present invention still further aims to provide an improved mechanism for dissipating or absorbing the jar or jump in the tape before it reaches the projecting position of a news projecting machine in which a looped rod or wire yieldingly engages the tape and deflects it out of its path of movement from the path of movement to the projecting position thereby to cause a loop to be formed in the tape between the printing mechanism and the tape engaging position of the wire in which loop the jar or jump will be dissipated to prevent transmitting the jar or jump to the portion of the tape disposed in the projecting position.

The present invention still further aims to provide an improved jar or jump dissipating mechanism which will cooperate to offer sufficient resistance when the printing mechanism is at rest to relieve the printing mechanism of most, if not all, of the pull being exercised by the drawing out mechanism which may be operating at the time.

The present invention still further aims to provide an improved structure of the character described having a minimum number of parts and which can be manufactured and assembled at comparatively low cost.

These and other features, capabilities and advantages of the invention will appear for the subjoined detail description of one specific embodiment thereof illustrated in the accompanying drawings, in which—

Fig. 1 is a sectional diagrammatic view showing a complete news projecting machine equipped with the present improvements.

Fig. 2 is a section on the line 2—2 of Fig. 1.

Fig. 3 is an enlarged fragmental section showing the jump dissipating mechanism in position when the printing mechanism is operating.

Fig. 4 is a section on the line 4—4 of Fig. 3.

Fig. 5 is an enlarged detail of the lever forming an essential part of the jump dissipating mechanism and the supporting bracket therefor, taken on the line 5—5 of Fig. 3.

Fig. 6 is an enlarged detail of the lever forming an essential part of the jump dis-

sipating mechanism and the supporting bracket therefor, taken on the line 6—6 of Fig. 3.

Fig. 7 is an enlarged detail showing the lever of the jump dissipating mechanism and tape when the printing mechanism is at rest and the drawing out mechanism is operating.

Fig. 8 is an enlarged detail of the drawing out mechanism.

Fig. 9 is an enlarged elevation of the drawing out mechanism illustrated in Fig. 8.

The improvements constituting the present invention are illustrated as equipped on news projecting machines such as illustrated in my copending application, Serial No. 82,295, filed January 19, 1926.

In such type of news projecting machines, the screen 1, as illustrated in Fig. 1, is supported in a screen housing 2 having a deflecting mirror 3, the housing 2 being preferably secured to a wall or the like by means of brackets 4.

Below such screen housing 2, there is situated the projecting machine proper, which consists essentially of a frame 5 having an upper platform 6 and a lower platform 7. On the upper platform 6 there is formed a housing 8 in one end of which there is located the mirror 9 which projects the images received through the opening 10 in the housing 8 up through the opening 11 in the housing 2 to the mirror 3 from which it is projected onto the screen 1.

At the other end of the housing 8 on the platform 6 there is provided a lamp casing 12 in which the lamp 13 is mounted. The rays from the lamp 13 are projected by the condensing lens 14 to the mirror 15 and from the mirror 15 deflected to the condensing lens 16. There is provided an opening adjacent to the condensing lens 16 over which there is preferably provided a glass tape guide 17 to permit the tape T to pass over the same, receive the rays from the lamp 12 to form images to be projected through the projecting lens supported in the lens housing 18 from which the images are projected to the mirror 9 and thereby deflected to the mirror 3 and by the mirror 3 deflected onto the screen 1.

In the present instance, see Fig. 4, there is attached to the casing 12 a bracket 19 for the reel 20 to support the roll 21 of tape T. The tape after leaving the reel 20 passes to the printing mechanism 22 and from there preferably passes over a guide 23 at a position preferably above and to the rear of the opening formed in the casing 12. The top of the casing 12, as indicated in Fig. 4 at 24, is preferably cut away a short distance and has a support 25 provided in the lower end of said cut-away portion, directly above and engaging the tape guide 17.

The guide 23 is preferably composed of

sheet metal and is looped at one end to form a guiding portion 23^a extending over the cutaway portion 24 and secured at its other end to the top of the casing 12. The tape T after leaving the printing mechanism first passes over the extended curved or looped portion 23^a, forming a support at one end and then is suspended in space, passing through the cut-away portion 24 to the support 25, at the other end of the space, the edges 24^a and 24^b of the cut-away portion 24 forming guides for the tape T in its passage to the support 25. Preferably as shown, the loop portion 23^a also terminates a short distance to the rear of the support 25.

After leaving the guide 23, the tape is deflected out of its path of movement by the bent or looped end 26 of the rod or lever L preferably composed of wire constituting a finger, and from there passes to the support or abutment 25 and then down over the guide 17 to the guide roller 27 supported on the bracket 28 secured to the lower platform 7 of the frame 5. From the roller 27 the tape passes to the guide roller 29 and then to and over the positively driven roller 30, the tape being frictionally held in engagement with the roller 30 by the roller 31 formed at the lower end of the bracket 32 pivoted at 33 to a support 33^a. The bracket 32 is fixed to the weight arm 34 on which is adjustably mounted the weight 35.

In the present instance, in order positively to drive the roller 30, it has secured thereto a gear 36 which meshes with the gear 37 mounted on the shaft 38 journaled in the support 39. On the shaft 38, there is secured a worm wheel 40 which meshes with the worm 41 forming an extension of the shaft 42 of the motor 43.

The weight 35 is so adjusted that the friction created by the roller 31 on the tape T will merely cause the tape T to be drawn out or fed out by its engagement with the roller 30, when the printing mechanism 22 is operating, but will permit the roller 30 to slip relative to the tape T when the printing mechanism 22 is at rest in order to prevent injury to the tape T.

The lever or rod L and its bent or looped end 26 serve several functions and form an essential part of the present improvements.

To mount the lever L, it has been found desirable to secure its straight end in a disc 44 by a thumb screw 45. The disc is pivoted near its edge, as indicated in Fig. 3, to the bracket 46. The bracket 46, as indicated in Fig. 6, is adjustably secured to the bracket 47 by a thumb screw 48 passing through the slot 49 formed in the bracket 46. The bracket 47, as indicated in Fig. 3, is secured to the top wall 50 of the housing 8.

From the foregoing, it will be seen that the looped end 26 of the lever L will normal-

ly extend downward due to the pivotal connection of the disc 45 with the bracket 46 and the weight of the lever L, so that the looped end 26 will normally maintain or impinge a portion of the tape T against the support 25 when the tape T is slack, as indicated in Fig. 3. It will also be seen that the looped end 26 projects a sufficient distance so that the guide 23 will obstruct its upward movement should it be raised, as indicated in Fig. 7, in which position it will maintain or impinge a portion of the tape T in engagement with the guide 23.

The operation of the projecting machine proper and the jump dissipating mechanism constituting the present improvements, will operate substantially as follows: When the printing mechanism or ticker 22 starts to operate it is desirable also to start the operation of the motor 43. With such printing mechanisms, the tape T will only be fed forward while the printing mechanism operates. In other words, if no quotations or the like are being transmitted, the ticker feed is at rest. In the embodiment illustrated, the motor 43 will continue to operate even though the ticker 22 is at rest.

When the ticker 22 is at rest, and the motor 43 is operating, it will draw the tape T substantially taut so that it will engage the looped end 26 of the lever L and due to the relative positions of the guide portion 23^a and shoulder 25 to the looped end 26, and the resulting curve formed in the tape T, the tension on the tape T will exercise an upward pull on the lever L to cause it to assume the position illustrated in Fig. 7, where the looped end 26 impinges the tape T against the guide portion 23^a. Thereupon, when the ticker again begins to operate, it will first relieve the tension in the tape T, form a loop, as indicated in Fig. 3, and permit the looped end 26 of the lever L to descend so that it will rest on the tape T and cause the tape T to hug the support 25 forming a friction creating surface. By means of the friction caused between the looped end 26, tape T and support 25, a retarding tendency will be exercised on the tape T, forming a frictional point of contact sufficient to permit a loop being maintained between the guide portion 23^a and the looped end 26, as indicated in Fig. 3, that is, so localize the loop, that its slack will not continue beyond the support 25, so that whatever jumps are transmitted to the tape T by the printing impulses of the printing mechanism will be absorbed by the loop thus formed and prevent the transmission of the jumps beyond the support 25. In turn, as the ticker starts to operate, the tape will again be free to be drawn down by the drawing out rollers 30 and 31, to cause a uniform travel of the tape T downward over the guide 17.

It is obvious that various changes and

modifications may be made to the details of construction without departing from the general spirit of the invention set forth in the appended claims.

I claim:

1. In a news projecting machine, the combination with a printing mechanism for printing news items on tape and the like, of a projecting mechanism, two spaced immovable supports, means for imparting a feeding impulse to the tape to advance the tape a unit of distance after each printing impression thereby feeding the tape from the printing mechanism over the two spaced supports to the projecting mechanism, and friction creating means for causing a loop to be formed between the two spaced supports, to dissipate the jump transmitted to the tape by the intermittent feeding impulse of the printing mechanism before the tape reaches the projecting mechanism. 70

2. In a news projecting machine, the combination with a printing mechanism for printing characters on a tape, of a projecting mechanism, means for imparting a feeding impulse to the tape to advance the tape a unit of distance after each printing impression, two spaced immovable supports, means for drawing the tape across said supports and through said projecting mechanism, and a finger engaging the tape and deflecting it out of its path of movement from one support to the other to form a loop between the printing mechanism and the projecting mechanism, to prevent the transmission of the jump caused by the intermittent feeding impulse of the printing mechanism to the tape when disposed in projecting position at the projecting mechanism. 80

3. The combination with a printing mechanism for printing news items on ticker tape, of a projecting mechanism, two spaced supports, means for imparting a feeding impulse to advance the tape a unit of distance after each printing impression thereby to feed the tape from the printing mechanism across the two supports to the projecting mechanism, means for drawing the tape through the projecting mechanism, and a friction creating element for engaging the tape and pressing it against one of said supports temporarily to anchor the tape against movement by the drawing means when the tape becomes taut due to the drawing movement of the drawing means and the arrest of the feeding means. 90

4. The combination with a printing mechanism for printing news items on a ticker tape, of an image projecting mechanism, means for imparting a feeding impulse to the tape toward the projecting mechanism after each printing impression, two spaced apart stationary supports disposed between said printing mechanism and said projecting mechanism, means for drawing the tape 100

from said printing mechanism across said supports and through said projecting mechanism, a finger adapted to engage the tape between said supports and deflect it out of its path of movement from one support to the other thereby causing the tape to engage said supports to create sufficient friction to form, between the printing mechanism and the projecting mechanism, a loop to dissipate the jump transmitted to the tape by the intermittent feeding impulse of said feeding means.

5. The combination with a printing mechanism for printing news items on a tape, of an image projecting mechanism for projecting images of the items printed on the tape, means for imparting a feeding impulse to advance the tape a unit of distance toward the projecting mechanism after each printing impression, a guide, a fixed support, the tape passing from the printing mechanism to the guide, then to the support, and then to the projecting mechanism, and a loop creating element extending between said guide and support to deflect the tape out of its path of movement when passing from the guide to the support to create a retarding action on the tape thereby to form a loop to absorb the jump transmitted to the tape by the intermittent feeding impulse of said feeding means.

6. The combination with a printing mechanism for printing news items on a tape, of an image projecting mechanism for projecting images of the items printed on said tape, means for imparting a feeding impulse to advance the tape a unit of distance toward the projecting mechanism after each printing impression, a guide, a fixed support, the tape passing from the printing mechanism to the guide, then to the support, and then to the projecting mechanism, a bracket, and a rod pivotally connected to said bracket and being looped at its free end, the looped end extending between said guide and support to deflect the tape out of its path of movement when passing from the guide to the tape to create a retarding action on the tape thereby to form a loop to absorb the jump transmitted to the tape by the intermittent feeding impulse of said feeding means.

7. The combination with a ticker having a printing mechanism for printing news items on a tape, and a feeding means for imparting a feeding impulse to advance the tape a unit of distance after each printing impression, of a lamp casing for an image projecting mechanism having a light rays emitting opening, a guide for the tape adjacent to said light opening, the upper portion of the lamp casing having a cut-away portion the sides of which form guides for the tape, a support formed in the lower portion of said cut-away portion adjacent to

said guide, a looped guide secured to the lamp casing above said cut-away portion and offset relative to the support, the tape passing from said printing mechanism to the looped guide, then into the cut-away portion, and then to the support before passing to the guide adjacent to the light opening, and a loop creating element extending into said cut-away portion between the looped guide and the support to deflect the tape out of its path of movement when passing from the looped guide to the support to create a retarding action on the tape thereby to form a loop to absorb the jump transmitted to the tape by the intermittent feeding impulse of said feeding means.

8. The combination with a ticker having a printing mechanism for printing news items on a tape, and a feeding means for imparting a feeding impulse to advance the tape a unit of distance after each printing impression, of a projecting mechanism having a lamp casing provided with a cut-away portion, the sides of which form guides for the tape, a looped guide secured to the casing above the cut-away portion, a support formed at the bottom of the cut-away portion and extending forwardly of said guide, the tape passing from the printing mechanism to the looped guide, then through the cut-away portion to the support and then to the projecting mechanism, a bracket, and a rod having one end pivotally connected to said bracket, the other end of the rod being looped and extending into the cut-away portion to maintain the tape in engagement with the support when the printing mechanism is operating to form a loop in the tape while passing through the cut-away portion.

9. The combination with a ticker having a printing mechanism for printing news items on a tape, and a feeding means for imparting a feeding impulse to advance the tape a unit of distance after each printing impression, of a projecting mechanism having a lamp casing provided with a cut-away portion, the sides of which form guides for the tape, a looped guide secured to the casing above the cut-away portion, a support formed at the bottom of the cut-away portion and extending forwardly of said guide, the tape passing from the printing mechanism to the looped guide, then through the cut-away portion to the support and then to the projecting mechanism, a bracket, a rod having one end pivotally connected to said bracket, the other end of the rod being looped and extending into the cut-away portion to maintain the tape in engagement with the support when the printing mechanism is operating to form a loop in the tape while passing through the cut-away portion, and means for exercising an even tension on the tape while passing through the projecting mechanism, said tension means con-

tinuing to exercise tension on the tape when the printing mechanism is at rest, the relative position of the looped guide and the looped end of the rod and support cooperating with the tape when the ticker is at rest and the tension means continue to operate, to raise the looped end of the rod to maintain the tape portion against the lower end of the looped guide.

10 10. The combination with a ticker having a printing mechanism for printing news items on a tape, and a feeding means for imparting a feeding impulse to the tape after each printing impression, of a project-

15 ing mechanism having a lamp casing provided with a cut-away portion, the sides of which form guides for the tape, a looped guide secured to the casing above the cut-away portion, a support formed at the bot-

20 tom of the cut-away portion and extending forwardly of said guide, the tape passing from the printing mechanism to the looped guide, then through the cut-away portion to the support and then to the projecting mech-

25 anism, a bracket, a disc pivotally connected to said bracket, and a rod having one end adjustably connected to said disc and its other end looped and extending into the cut-away portion to deflect the tape

30 out of its path of movement when passing from the looped guide to the support to form a loop for absorbing the jump transmitted to the tape by the intermittent feeding impulse of said feeding means.

11. The combination with a ticker having a printing mechanism for printing news items on a tape, and a feeding means for imparting a feeding impulse to advance the tape after each printing impression, of a project-

35 ing mechanism, means for drawing the tape from the printing mechanism to the projecting mechanism, a stationary friction creating surface, and means for causing the tape to hug said friction creating surface

40 when said printing mechanism operates to form a loop in the tape to absorb the jars transmitted to it by the intermittent feeding impulse of said feeding means.

12. The combination with a ticker having a printing mechanism for printing news items on a tape, and a feeding means for imparting a feeding impulse to the tape after each printing impression, of a projecting

45 mechanism having a vertically positioned light aperture, two spaced apart supports, means for feeding the tape from the printing mechanism over the two supports to the projecting mechanism, means for drawing the tape from said projecting mechanism as

50 it is fed thereto, and a finger adapted to engage the tape between said supports and deflect it out of its direct path of movement from one support to the other to impinge the tape between said finger and one of said supports thereby to retard the movement of

the tape at such point to form a loop in the tape when said feeding means is operating to absorb the jars transmitted to it by the intermittent feeding impulse of said feeding means.

70

13. The combination with a ticker having a printing mechanism for printing news items on a tape, a feeding means for imparting a feeding impulse to the tape after each printing impression, and having a guide for 75 the tape, of a projecting mechanism having a vertically extending light aperture disposed at an angle to said guide, two spaced apart supports, means for feeding the tape from the printing mechanism over said sup- 80 ports to the projecting mechanism, means for drawing the tape from the projecting mechanism as it is fed thereto, and a finger adapted to engage the tape between said sup- 85 ports and deflect it out of its direct path of movement from one support to the other and to impinge the tape between said finger and one of said supports when said feeding means comes to rest, thereby to oppose the drawing 90 action of said drawing means and protect said feeding means from the strain that would otherwise be transmitted by said drawing means.

14. In a news projecting machine, the combination with a printing mechanism for 95 printing news items on tape and the like, of a projecting mechanism, means for imparting a feeding impulse to the tape to advance the tape a unit of distance after each print- 100 ing impression thereby feeding the tape from the printing mechanism to the projecting mechanism, a support adjacent to the projecting mechanism and spaced from the feeding means, friction creating means for press- 105 ing the tape into engagement with said sup-

port to cause a slack loop to be formed in the space between said support and said feeding means, said loop functioning to dissipate the jump transmitted to the tape by the feeding impulse of the feeding means before the tape reaches the projecting mechanism, and means for drawing the tape through the projecting mechanism and co- 110 operating with said friction creating means to maintain taut the portion of the tape 115 while passing said projecting mechanism during the operation of the feeding means.

15. In a news projecting machine, the combination with a printing mechanism for printing news items on tape and the like, of 120 a projecting mechanism, means for imparting a feeding impulse to the tape to advance the tape a unit of distance after a given printing impression thereby feeding the tape from the printing mechanism to the project- 125 ing mechanism, a support located between the projecting mechanism and the feeding means and being spaced from said feeding means, a finger for pressing the tape into engagement with said support to cause a free 130

loop to be formed between said support and said feeding means, said loop functioning to dissipate the jump transmitted to the tape by the feeding impulse of the feeding means 5 before the tape reaches the projecting mechanism, and means for drawing the tape through the projecting mechanism and co-operating with said finger to maintain taut the portion of the tape passing the projecting mechanism during the operation of the feeding means.

16. In a news projecting machine, the combination with a printing mechanism for printing news items on tape and the like, of 15 a projecting mechanism, means for feeding the tape through the projecting mechanism, an abutment located between the projecting mechanism and the printing mechanism, and a finger for pressing the tape into engagement with said abutment and functioning to dissipate the jump transmitted to the tape by the printing mechanism before the tape 20 reaches the projecting mechanism.

17. The combination with a ticker having a printing mechanism for printing news 25 items on a tape and a feeding mechanism for imparting a feeding impulse to advance the tape after each printing impression, of a projecting mechanism, a jump dissipating device including a friction creating surface 30 between said ticker and said projecting mechanism and means for causing the tape to hug said friction creating surface when said printing mechanism operates, and friction drawing means for drawing the tape 35 from the feeding mechanism through the projecting mechanism, said drawing means being free to slip relative to said tape when said feeding mechanism comes to rest but at the same time cooperating with said feeding 40 mechanism and jump dissipating device to create sufficient tension in said tape when the operation of said feeding mechanism is discontinued to maintain the tape taut at the projecting position.

BARTON A. PROCTOR.
